Primary Examiner — T Chase Nelson

Assistant Examiner — Kelly L Gross

(57) **CLAIM**

The ornamental design for a sphygmomanometer, as shown and described.

DESCRIPTION

1. Sphygmomanometer

1.1 : Perspective

1.2 : Front

1.3 : Back

1.4 : Left

1.5 : Right

1.6 : Top

1.7 : Bottom

1.8 : Perspective

Fig. 1.1 is a top, front, left side perspective view of a sphygmomanometer, showing the claimed design; fig. 1.2 is a front elevation view thereof; fig. 1.3 is a back elevation view thereof; fig. 1.4 is a left side elevation view thereof; fig. 1.5 is a right side elevation view thereof; fig. 1.6 is a top plan view thereof; fig. 1.7 is a bottom plan view thereof; and fig. 1.8 is a bottom, back, right side perspective view thereof; the dashed broken lines in the drawing depict portions of the sphygmomanometer that form no part of the claimed design.

1 Claim, 8 Drawing Sheets(56)
